UNITED STATES PATENT OFFICE.

EMORY B. WHITE, OF CLARION, IOWA.

CHECK-ROW CORN-PLANTER.

SPECIFICATION forming part of Letters Patent No. 294,555, dated March 4, 1884.

Application filed September 25, 1883. (No model.)

To all whom it may concern:

Be it known that I, EMORY B. WHITE, a citizen of the United States, residing at Clarion, in the county of Wright and State of Iowa, have 5 invented certain new and useful Improvements in Check-Row Corn-Planters, of which the following is a specification, reference being had therein to the accompanying drawings.

This invention relates to improvements in 10 check-row corn-planters, the object of which is to drop the corn with certainty at regular intervals, and to adjust the dropping device in such manner that different quantities of corn may be dropped at pleasure. These objects 15 are attained by the mechanism illustrated in the accompanying drawings, forming a part of this specification, in which—

Figure 1 is a side elevation of the machine. Fig. 2 is a plan view. Figs. 3, 4, and 5 are 20 detailed views of several of the parts of the machine.

The letters A and B B' represent the frame of the machine.

D are metal runners attached in front to the 25 frame B and in the rear to the frame B'. These runners are forked in the rear, as indicated in the plan view.

C is a hopper for the reception of the corn or seed.

30 F are balls secured to the spokes of the wheel O, and are for purpose of marking the hills, so that the operator may know where to start at the ends of the field, it being necessary to start in right in order to do satisfactory work.

35 E are cams secured to the spokes of the wheels O, and are intended to operate the sliding bar H and give it reciprocating motion by striking against the friction-rollers H', secured in the ends thereof, at each revolution of the 40 wheels O, whereby motion is imparted to the bar L by means of the rods J J, which connect the bars L and H to each other.

45 i are pins in the frame B', which are intended as guides to keep the bar L in place, and at the same time to permit the bar to slide freely back and forth, and thus actuate the feeding

devices (to drop the corn) within the hoppers C, by agitating the corn or seed therein. The bar H has slots I, through which are inserted the screws K, securing the bar to the frame B', 50 and at the same time permitting the bar to slide back and forth.

G are sharp-pointed metal spokes secured to the wheels and hub O, which are keyed or otherwise fastened to the shaft N, and as 55 the machine is drawn over the ground the points of the spokes penetrate the surface of the earth and cause the rotation of the wheels O and shaft N. The shaft N extends through the frame B', and is provided with cast-iron 60 feed-wheels P', having holes P" in the faces thereof provided with screws P, which are intended to adjust the size of the opening for the reception of the grains of corn, so as to vary the quantity which may be dropped at 65 each revolution of the shaft N and wheels P', which are placed directly under the opening at the bottom of the hoppers C.

Having described my invention, what I desire to secure by Letters Patent, and to claim, 70 is—

1. In a check-row corn-planter, the wheel or hub O, having sharp-pointed metal spokes G, provided with balls F and cams E, in combination with reciprocating bar H, having friction-rollers H' and rods J, adapted to operate 75 sliding bar L, as described, and for the purposes set forth.

2. In a check-row corn-planter, the shaft N, having wheels O, with sharp-pointed metal 80 spokes G, provided with cam E, in combination with reciprocating bar H, having friction-rollers H', rods J, bar L, guide-pins i, hoppers C, and feed-wheel P', having adjusting-screws P and holes P", as described, and for the purposes set forth.

In testimony whereof I affix my signature in presence of two witnesses.

EMORY B. WHITE.
